(57) **CLAIM**

The ornamental design for a mounting assembly, as shown and described.

DESCRIPTION

FIG. 1 is a top perspective view of the cover portion of a mounting assembly showing our new design, the cover portion shown separated for ease of illustration.

FIG. 2 is a left side plan view of the cover of FIG. 1.

FIG. 3 is a right side plan view of the cover of FIG. 1.

FIG. 4 is a front plan view of the cover of FIG. 1.

FIG. 5 is a rear plan view of the cover of FIG. 1.

FIG. 6 is a top plan view of the cover of FIG. 1.

FIG. 7 is a bottom plan view of the cover of FIG. 1.

FIG. 8 is a top perspective view of the bracket portion of a mounting assembly showing our new design, the bracket portion shown separated for ease of illustration.

FIG. 9 is a bottom perspective view of the bracket of FIG. 8.

FIG. 10 is a left side plan view of the bracket of FIG. 8.

FIG. 11 is a right side plan view of the bracket of FIG. 8.

FIG. 12 is a front plan view of the bracket of FIG. 8.

FIG. 13 is a rear plan view of the bracket of FIG. 8.

FIG. 14 is a top plan view of the bracket of FIG. 8.

FIG. 15 is a bottom plan view of the bracket of FIG. 8.

FIG. 16 is a perspective top view of a mounting assembly comprising the cover of FIG. 1 assembled with the bracket of FIG. 8.

FIG. 17 is another perspective top view of the mounting assembly of FIG. 16.

FIG. 18 is a left side plan view of the mounting assembly of FIG. 16.

FIG. 19 is a right side plan view of the mounting assembly of FIG. 16.

FIG. 20 is a front plan view of the mounting assembly of FIG. 16.

FIG. 21 is a rear plan view of the mounting assembly of FIG. 16.

FIG. 22 is a top plan view of the mounting assembly of FIG. 16; and,

FIG. 23 is a bottom plan view of the mounting assembly of FIG. 16.

In the drawings, the broken lines form no part of the claimed design.
